UNITED STATES PATENT OFFICE.

CHARLES L. WOOD, OF KANSAS CITY, MISSOURI.

SANITARY FINGER-BOWL SPRAY.

1,232,151.

Specification of Letters Patent.

Patented July 3, 1917.

Application filed May 22, 1914. Serial No. 840,246.

To all whom it may concern:

Be it known that I, CHARLES L. Wood, a citizen of the United States, residing at Kansas City, in the county of Jackson and 5 State of Missouri, have invented certain new and useful Improvements in Sanitary Finger-Bowl Sprays; and I do declare the following to be a full, clear, and exact description of the invention, such as will enable others skilled in the art to which it 10 appertains to make and use the same.

The present invention relates to improvements in finger-bowls and the like, and aims to provide a device which will be in all respects sanitary and adapted to replace, to a greater or less extent, as desired, the individual finger-bowl now commonly used. With this end in view, the invention comprises a liquid-containing vessel partially 20 inclosed by an outer receptacle for receiving the waste liquid, together with a device associated with the inner vessel and adapted to be engaged by the palm of the hand of the user and thereby actuated for the purpose of ejecting a spray of the liquid upon the portions of the hand surrounding the engaged portion of the device. The device as thus constructed may be used for various 25 purposes, as for example, to dispense toilet waters, perfumes, and the like.

Having the above-stated general object in view, the invention will now be described in connection with the accompanying drawing showing one form of the same as embodied in practice, after which those features and combinations which are deemed to be novel will be severally specified in the appended claims.

In the drawing—

40 Figure I is a central vertical section through the device; and

Fig. II is an elevation of the same with portions of the outer receptacle and the inner liquid-containing vessel broken away to disclose the spraying member.

Referring to the drawing, the outer bowl or waste-liquid receptacle 2 is of a size sufficient to receive and partially inclose the inner closed vessel 4 which is designed to 50 contain the liquid (not shown) to be dispensed by the device. The vessel 4 is adapted to rest at the bottom of the bowl 2 upon the margins of an opening 6 which leads into a chamber 8 within the base of the bowl 2. These receptacles 2 and 4 may be of any 55 form which may be desired, but it is pre-

fferred to make the inner vessel 4 of downwardly tapered form, as illustrated, in order that its filling opening 10 and the plug 12 therefor may be located practically out of view, thereby leaving the top of the inner vessel of smooth and unbroken appearance.

Secured within the inner vessel 4 and extending axially therethrough is the spraying member, which comprises a plunger casing 14 fitted through the base of the vessel 4 and externally threaded to receive a cap member 16, the upper edge of which carries a gasket 18 to be clamped against the outer margins of the opening 6 to form a liquid-tight joint. A coil spring 20 is supported by the cap 16 within the casing 14, where it in turn supports the plunger 22 in normally raised position. This plunger moves from one side to the other of a series of 75 openings 24 in the casing 14 adapted to admit liquid into the plunger chamber from the vessel 4. Threaded through the plunger is a hollow plunger stem 26, its lower end being always in communication with the 80 plunger chamber. This stem operates through a hollow extension 28 to the casing 14, the upper end of this extension being fitted through the top of the vessel 4 and externally threaded to receive a nut 30 85 for coöperating with the cap 16, whereby the casing 14 and its extension are held securely in place. A series of openings 32 are provided in the top of the casing 14 to permit the liquid to leave the plunger chamber 90 under the action of the spring in lifting the plunger.

The top of the plunger stem is also threaded for the purpose of mounting thereon the spray-head 34, which is designed to protrude sufficiently above the outer edge of the outer bowl 2 to be readily engaged by the hand of a person using the device. The spray-head 34 is provided with a series of small lateral openings 36 through which the 100 liquid is ejected in fine spray form whenever the device is operated. The shank of the spray-head is of such length that its lower end will, when the plunger is depressed, come in contact with the upper end of the 105 extension 28, which thus acts as a stop limiting the movement of the plunger. By adjusting the position of the spray-head upon the plunger stem, therefore, the length of the plunger stroke may be varied and the 110 amount of the liquid dispensed at each operation correspondingly regulated.

Normally the spring 20 maintains the plunger elevated above the opening 24, so that the chamber of the casing 14 is allowed to be filled with the liquid. In operation, the palm of the hand is brought centrally over the bowl 2 and the hand partially closed over and around the spray head 34. The device is then operated by pressure downward upon the spray-head, thereby forcing the plunger, against the action of the spring, down past the openings 24, closing the latter and expelling a portion of the liquid below said openings up through the plunger stem 26 and out through the openings 36 in the form of a light spray which moistens the portions of the hand opposite these openings. On removing the hand, the spring 20 restores the parts to original position, allowing the plunger casing to be filled again with the liquid.

The principal points of advantage in this construction are its obvious ease and quickness of operation, and the sanitary features 25 characterizing its mode of operation as a finger-bowl. Water once used for spraying the palm of the hand drips into the outer bowl, gradually filling first the space 8 within the base of said bowl and then the 30 space above the opening 6, and can not be used a second time, a fresh supply of liquid being always pumped from the inner vessel 4. The device is designed with a view to continuous use, no change or adjustment 35 of the same being necessary until the inner vessel 4 requires a new supply of the liquid, or until the outer bowl requires to be emptied of the waste liquid, at which times the inner vessel and its attached parts are simply 40 lifted out of the outer bowl. By the arrangement of the spray-head so that its adjustment may vary the length of the plunger stroke, it is apparent that the amount of the liquid dispensed at each stroke may be very 45 nicely regulated.

While the foregoing represents what is now conceived to be the preferred form of the invention, the right is reserved to such minor changes in form as may fairly fall within the scope of the appended claims.

Claims:

1. In a device of the character described, the combination of an outer liquid receptacle, an inner closed liquid receptacle supported within said outer receptacle, and in it closed thereby, and a device associated with

said inner receptacle and operative to deliver a spray of liquid from the inner to the outer of said receptacles.

2. In a device of the character described, 60
the combination of an outer liquid receptacle, an inner closed liquid receptacle supported upon the bottom of said outer receptacle and inclosed thereby, and a pumping device projecting from said inner receptacle and adapted, upon being subjected to downward pressure, to eject a liquid spray from the inner receptacle outward from points below the upper end of said pumping device in the direction of the interior 70 walls of the outer receptacle. 65

3. A finger-bowl spray comprising an outer receptacle, a closed liquid container within said receptacle, a plunger chamber secured within said container and having 75 openings communicating therewith, a plunger operating within said chamber and provided with a hollow plunger stem projecting from the top of said container, and a spray member mounted on the top of said 80 stem and provided with outwardly facing spray openings, whereby downward movement of the plunger ejects a spray of liquid from the container through said spray member into the outer receptacle. 85

4. In a finger-bowl spray, the combination with a liquid receptacle having top and bottom openings, of a plunger device comprising a casing fitting through said bottom opening and having a tubular stem fitting 90 through said top opening, a cap member threaded on the lower end of said casing, a nut carried by the upper end of said stem and co-operating with said cap member to clamp said casing within the receptacle, said 95 casing having openings communicating with said receptacle and forming a plunger chamber, a plunger operating within said chamber and provided with a hollow plunger stem fitting in said tubular stem, a spray- 100 member carried by the upper end of said plunger stem, and a coil spring supported by said cap member within said chamber and acting to hold said plunger normally elevated above said communicating openings. 105

In testimony whereof I affix my signature in the presence of two witnesses.
